UNITED STATES PATENT OFFICE.

SERENO E. NORTON, OF EVANSTON, ILLINOIS.

MATCH-BOX.

SPECIFICATION forming part of Letters Patent No. 651,379, dated June 12, 1900.

Application filed January 13, 1900. Serial No. 1,269. (No model.)

To all whom it may concern:

Be it known that I, SERENO E. NORTON, a citizen of the United States, residing in Evanston, in the county of Cook and State of Illinois, have invented a new and useful Improvement in Match-Boxes, of which the following is a specification.

My invention relates to improvements in pocket match-boxes.

10 The object of my invention is to provide a simple, convenient, neat, efficient, and cheap construction of sheet-metal match-box without soldering or riveting together of parts, so that the body of the box may be made out of 15 metal sheets which are enameled, japanned, or otherwise decorated while in the flat and in which the parts of the box may all be put together without marring or injuring the decoration and so that the boxes may be rapidly and cheaply manufactured, thus adapting 20 the boxes to be furnished in large quantities and at small cost for advertising and other purposes.

25 My invention consists in the novel construction of parts and devices and in the novel combinations of parts and devices herein shown and described, and specified in the claims.

30 In the accompanying drawings, forming a part of this specification, Figure 1 is a perspective view of a match-box embodying my invention. Fig. 2 is a central longitudinal section. Fig. 3 is a cross-section on line 3 3 of Fig. 2; Fig. 4, an enlarged cross-section on 35 line 4 4 of Fig. 2. Fig. 5 is a detail cross-section of the body of the box. Fig. 6 is an enlarged detail section on line 6 6 of Fig. 2; Fig. 7, a perspective view of the cover; Fig. 8, a detail edge view of the folded socket- 40 strip which unites the edges of the box-body and holds the spring. Fig. 9 is a section on line 9 9 of Fig. 2. Fig. 10 is an enlarged detail section of the socket-strip, and Fig. 11 is a detail view of the kick-spring.

45 In the drawings similar letters of reference indicate like parts in all the figures.

In said drawings, A represents the sheet-metal body of the box, the same being formed out of a flat sheet-metal blank by folding the 50 same into the desired shape in cross-section and forming the abutting oppositely-turned hooks or curved flanges a a on its meeting

edges at the back a' of the body. The body A is also provided at its two flat sides a² a³, near the lower or bottom end of the body, with 55 two beads or corrugations a³ a⁴, forming a groove a⁵ between them, the upper bead or corrugation a⁴ being preferably larger than the lower one a³.

B is a folded socket-strip having hooks or 60 flanges b b turned on its side edges to form a socket which telescopes over the corresponding hooks or flanges a a, turned on the meeting edges of the body A, and which thus serves to firmly unite or seam together without rivets or solder the two meeting edges of the body. The hooks or flanges b on one side of the socket-strip do not extend along the full length of the socket-strip, as the same is provided with similarly but oppositely turned 65 hooks or flanges b' for a portion of its length to form a socket to receive and hold firmly in place the spring C, by which the hinged cover 70 D of the box is thrown open. The socket-strip B is further provided at its upper end 75 with an integral tongue, which is rolled or folded into an eye b² for the hinge-pin of the cover. The cover D, which is made from a single sheet-metal blank, has a flange or rim d at its sides, back, and front and an inclined 80 integral kicker or tongue d', which is engaged by the upper end of the kick-spring C to cause the hinged cover to be thrown open by said spring. The cover D is also provided at its back with integral eyes d² d², one on each side 85 of the kicker d', to receive the hinge pin or pivot d³, by which the cover is hinged to the socket-strip and thus to the box-body.

The body A is provided with an external bead or corrugations a⁶ at its sides near its 90 upper end to form shoulders for the rim or flange d of the cover D to shunt or abut against when the cover is closed. At the upper or cover end of the body its two sides a² a² extend above or beyond its back a' and the upper or eye end of the socket-strip B, so that after the cover is hinged to the socket-strip and the hinge pin or pivot d³ inserted through the eyes d² d² and b² and the socket-strip then inserted in position and forced home 100 over the hooks or flanges a a of the body the projecting upper ends a⁷ a⁷ of the box sides a² a² will fit over or embrace the ends of the hinge pin or pivot d³, and thus prevent said

pin from slipping out. The front corners a^8 of the box sides are clipped off or inclined, and the back corners a^9 are preferably also inclined, but not sufficient to prevent the projecting ends a^7 of the box sides a^2 to slightly overlap the ends of the hinge-pin d^3 .

F is the bottom of the box, which, like the cover D, is stamped up out of a single sheet-metal blank. It has an integral rim or flange f , furnished with a slightly-inturned upper edge f' to enter and fit in the groove a^5 in the body A, and it is further provided with a marginal groove or channel f^2 to receive the extreme lower end or edge a^{11} of the box-body and slightly wedge or incline it outward when the body is pushed forcibly into the bottom. The inclined or wedge-acting marginal groove or channel f^2 in the bottom F is formed by curving the bottom upward, thus giving the bottom a wide external channel f^3 on its outside, which is furnished with transverse corrugations f^4 to produce a rough or match-striking surface in this wide channel of the bottom. The eye or rolled tongue b^2 is preferably first formed on the socket-strip B, so that the edge folds b may overlap the end b^4 of the hinge-pivot eye b^2 , and thus strengthen said eye.

To firmly secure the bottom F to the body A, it is simply necessary to insert the latter within the former and forcibly push or telescope them together, when the bead or shoulder a^4 will further curve or turn the extreme inturned edge f' into the groove a^5 on the body, and the inclined or wedging marginal channel f^2 in the bottom will force or curve the extreme lower end of the body into said marginal channel, thus securely locking the two parts together without solder or rivets.

To seam or unite together the meeting edges of the body, the socket-strip B is simply telescoped over the hooks or flanges a on the body, after which the interlocked heads or flanges on the socket-strip and body may be slightly bumped or pressed together to more rigidly and closely unite or lock together these parts. Before the socket-strip B is applied to the body the cover D should be hinged to the socket-strip, or otherwise the projecting ends a^7 of the box sides a^2 would interfere with the easy insertion of the hinge-pin d^3 , and for convenience of bumping or pressing the interlocked hooks or flanges of the body and socket-strip together I ordinarily apply the bottom F to the body after, and not before, the socket-strip is applied. The kick-spring C, which is made slightly tapering, is fixed in place by simply firmly crowding it into its socket in the socket-strip.

As my match-box consists of but six separate pieces, inclusive of the hinge-pin, and as each and all the parts are of simple form and capable of being rapidly and cheaply made, and as all the parts may be easily and quickly assembled and secured together without any soldering or riveting, it will be understood that my box may not only be manufactured

and furnished at small cost, but also readily made of enameled or decorated sheet metal without danger of marring or injuring the decorated surface.

I claim—

1. A sheet-metal match-box without solder or rivets, comprising in combination a body having hooks or curved flanges on its meeting edges, a socket-strip having hooks or flanges embracing the hooks or flanges on the meeting edges of the body, and provided with hooks or flanges on its opposite face to form a socket to receive and hold the spring, and provided with an eye at its upper end to receive the hinge-pivot of the cover, a spring fitting in said socket of the socket-strip, a cover having an integral kicker or tongue to engage the spring and eyes for the hinge-pin, and a bottom provided with a rim or flange having an inturned upper edge and an inclined or wedging marginal groove to engage the extreme lower edge of the end of the body, said body having a shoulder and a groove to engage the upper edge of the bottom flange or rim, substantially as specified.

2. In a sheet-metal match-box, the combination with the body having hooks or flanges on its meeting edges at its back, of a socket-strip embracing said hooks or flanges on the body and provided with a socket to receive the spring, substantially as specified.

3. In a sheet-metal match-box, the combination with the body having hooks or flanges on its meeting edges at its back, of a socket-strip embracing said hooks or flanges on the body and provided with a socket to receive the spring, and a cover hinged to the socket-strip, substantially as specified.

4. In a sheet-metal match-box, the combination with the body having hooks or flanges on its meeting edges at its back, of a socket-strip embracing said hooks or flanges on the body and provided with a socket to receive the spring, a cover hinged to the socket-strip, a spring, and an integral projection on the cover engaging the spring, substantially as specified.

5. The combination with a sheet-metal body A, having hooks or flanges a at its back meeting edges, a spring and a socket-strip having hooks or flanges b embracing said hooks or flanges on the back of the body and provided with a socket to receive said spring, substantially as specified.

6. The combination with a sheet-metal body A, having hooks or flanges a at its back meeting edges, and a socket-strip having hooks or flanges b embracing said hooks or flanges on the back of the body, said socket-strip having a hinge-pivot eye at its upper end, substantially as specified.

7. The combination with the body, of a metal strip secured at the back of the body and provided with a coiled eye at its upper end to receive the hinge-pivot of the cover, and a one-piece sheet-metal cover D having integral flange d provided at its back with

integral kicker-tongue d' , substantially as specified.

8. The combination with the body, of a metal strip secured at the back of the body and provided with a coiled eye at its upper end to receive the hinge-pivot of the cover, and a one-piece sheet-metal cover D having integral flange d provided with an integral tongue d' at its back and a cover hinged to said strip, the sides of said body extending above the hinge of the cover and overlapping the ends of the hinge-pin to keep it in place, substantially as specified.

9. The combination with body A having beads or shoulders $a^3 a^4$ and groove a^5 between them, of a bottom F having flange or rim f and inclined or wedging marginal channel f^2 locking the bottom and body together, substantially as specified.

10. The combination with body A, having beads or shoulders $a^3 a^4$ and groove a^5 between them, of bottom F having flange or rim f and inclined or wedging marginal channel f^2 locking the bottom and body together, the

upper edge of the bottom flange being turned inward and the lower edge of the body being turned outward, substantially as specified.

11. The combination with body A, having beads or shoulders $a^3 a^4$ and groove a^5 between them, of bottom F having flange or rim f and inclined or wedging marginal channel f^2 locking the bottom and body together, the upper edge of the bottom flange being turned inward and the lower edge of the body being turned outward, said bottom F having a roughened wide channel f^3 on its outside, substantially as specified.

12. The combination with body A having flanges $a a$, of socket-strip having flanges $b b$ and $b' b'$ and eye b^2 , spring C, and cover D having rim d , kicker-tongue d' and eyes $d^2 d^2$, substantially as specified.

13. The combination with body A having flanges $a a$, of socket-strip having flanges $b b$ and $b' b'$ and eye b^2 , spring C, and cover D having rim d , kicker-tongue d' and eyes $d^2 d^2$ and bottom F secured to said body by interlocking grooves and flanges, substantially as specified.
